United States Patent Office.

THE OODULE J. V. ROZ, OF NEW YORK, N. Y.

Letters Patent No. 85,965, dated January 19, 1869.

AUXILIARY KEY-BOARD FOR PIANOS, &c.

The Schedule referred to in these Letters Patent and making part of the same.

To all whom it may concern:

Be it known that I, THEODULE J. V. ROZ, of the city and State of New York, have invented and made a certain new and useful Improvement in Key-Boards for Pianos and other Musical Instruments; and I do hereby declare the following to be a full, clear, and exact description of the said invention, reference being had to the annexed drawing, making part of this specification, wherein—

Figure 1 is a plan illustrative of the manner in which my elementary key-board is applied to the usual key-board.

Figure 2 is a section of the same transversely.

Figure 3 represents a modification of the connections between the respective keys.

Figures 4 and 5 are transverse sections representing the said improved elementary key-board with the solfeggio-attachment.

Similar marks of reference denote the same parts.

In Letters Patent granted to me, April 30, A. D. 1867, an elementary key-board is shown, and also a solfeggio-attachment.

My present invention is an improvement upon the same, whereby the mechanism is rendered much more simple, and less liable to derangement, and the whole key-board is rendered light and portable, and capable of easy application to any piano or other key-board.

The nature of my present invention consists in the mechanism for raising the back ends of the levers that intervene between the elementary and the main key-board, so that the elementary key-board can be applied with facility to the main key-board, without the risk of injury to the levers, and then the said levers can be pressed down upon the notes.

I also fit the elementary key-board adjustably upon slide-supporting arms, in order that the key-board may be adapted to the different thicknesses of the bottom of pianos below the notes.

In the drawing—

a *a* represent the notes (or some of them) of the small or elementary key-board. These notes are to be of such a width that the key-board is adapted to the small hand of the child or person for whose use the key-board is especially intended.

b b are the levers intervening between the key-board *c* of the instrument and the elementary key-board *a*.

These levers *b* are provided, at their back ends, with regulating-screws, 5, with button-ends, to take the notes of the piano; and the levers *b b* diverge, as illustrated in fig. 1, so as to pass from the notes of the smaller or elementary key-board *a* to the corresponding notes *c* of the main key-board.

The elementary key-board is fitted in a case or cabinet, formed of the sides *e*, bottom *f*, and a front of any desired character, and a hinged flap might be provided to enclose the key-board when not in use.

Upon the bottom of the piano fixed-slides, *g*, are attached, into which the supporting-arms *h* are slipped when the movable elementary key-board is applied to the piano.

These arms *h* are attached to the case *e* by means of bolts passing through slots, as at *i*, so that the case

and elementary key-board can be raised or lowered to accommodate the position of the main key-board.

The fulcrum-forks 2, of the levers *b*, are attached to the under side of the hinged leaf *k*, the same being united to the case *e* by the hinges 3, at the front edge, and resting upon the arms *l*.

The clamping-screws 4 hold this leaf *k* down to the arms *l*, but when these are released, the leaf *k* can be raised by hand or by springs, so as to lift the range of fulcrum-forks 2, and thereby raise the regulating-screws 5 entirely off the notes of the piano, so that the elementary key-board can be applied to or withdrawn from the piano with convenience.

The connection between the levers *b* and elementary key-board *a* may be by the lifters *m*, figs. 2, 4, and 5, or it may be by the tension-rod *m'*, fig. 3, the parts being arranged as most convenient for the given instrument, with the elementary key-board as high as the main key-board, as in fig. 4, or lower than the same, as in fig. 3.

In order to hold the levers *b* up, when raised from the main key-board, I employ the bar *n*, that is operated by the projecting knobs 7, and is slipped back below the levers *b*, as in fig. 3, or above them, as in fig. 2, the section of said bar *n* being of a wedge-form.

My solfeggio-attachment, as applied with this key-board, consists in the bent lever *o*, applied to each key in such manner that the end of this lever *o* will rise above the case or the table *p*, and expose the name of the note, or its position on the musical scale, by a card, *o'*, or other printed device attached to said lever *o*.

In fig. 4, this solfeggio-attachment is worked by the key *a*, pressing directly upon the short end of the lever *o*.

In fig. 5, a finger, 8, is shown as rising above the key, to operate said lever *o*.

The regulating-screws, 5, pass through plates, 10, that are attached to the levers *b* by a screw, so that the said screws 5 can be brought correctly over the centre of each note, *c*, should there be any slight irregularities or variations in the key-board of the piano.

What I claim, and desire to secure by Letters Patent, is—

1. The leaf *k*, hinged to the case of the elementary key-board, and carrying the fulcrum-forks 2, of the levers *b*, in combination with the clamping-screws 4, or their equivalents, as and for the purposes set forth.

2. The elementary key-board, sustained adjustably upon the arms *h* that slide into supports below the bed of the piano, substantially as and for the purposes set forth.

3. The plates 10 and regulating-screws 5, applied to and combined with the levers *b*, and elementary key-board *a*, as and for the purposes set forth.

In witness whereof, I have hereunto set my signature, this 18th day of November, 1868.

T. J. V. ROZ.
